UNITED STATES PATENT OFFICE.

FRANKLIN P. BURKHARDT, OF SPRINGFIELD, OHIO, ASSIGNOR TO THE ANDERSON TOOL COMPANY, OF ANDERSON, INDIANA, A CORPORATION OF INDIANA.

MEAT-SLICER.

No. 857,155.

Specification of Letters Patent.

Patented June 18, 1907.

Application filed March 12, 1904. Serial No. 197,776.

To all whom it may concern:

Be it known that I, FRANKLIN P. BURKHARDT, a citizen of the United States, residing at Springfield, in the county of Clark and State of Ohio, have invented a new and useful Meat-Slicer, of which the following is a specification.

This invention relates to meat slicers.

The object of the invention is to produce a machine for slicing meat or other articles which is simple in construction and efficient in operation.

A further object of the invention is to provide a slicing machine of simple construction, wherein the meat or other article to be sliced is automatically progressed or fed toward the plane of operation of the cutter.

A further object of the invention is to provide means whereby the depth of cut made by the cutter may be adjustably regulated.

Other objects of the invention will appear more fully hereinafter.

The invention consists substantially in the construction, combination, location and relative arrangement of parts, all as will be more fully hereinafter set forth, as shown in the accompanying drawings, and finally pointed out in the appended claims.

Referring to the accompanying drawings, and to the various views and reference signs appearing thereon, — Figure 1 is a view in top plan of a meat slicing machine embodying the principles of my invention. Fig. 2 is a view in side elevation of the same. Fig. 3 is a detached broken detail view in section of a part of the automatic feeding mechanism. Fig. 4 is a detached detail view of a part of the means for adjustably regulating the depth of cut made by the cutter. Fig. 5 is an end elevation looking from the right of Fig. 2.

The same part is designated by the same reference sign wherever it occurs throughout the several views.

In the drawings reference sign 1 designates the main frame of the machine, which is made in one piece and upon which are supported the various working parts of the mechanism.

Reference sign 2 designates the preferred form of slicing cutter, and is in the form of a disk cutter and is carried by an enlarged wheel 3, mounted upon a shaft 4, journaled in suitable bearings formed in the main frame. Rotation may be imparted to shaft 4 in many convenient ways. I have shown the preferred simple arrangement, wherein a

gear 5, mounted on shaft 4, is arranged to intermesh with a driving gear 6, carried by a sleeve 7, mounted upon a fixed stud 8. A crank handle 9, suitably connected to gear 6, affords means for imparting rotation to shaft 4. By mounting the cutter or knife 2 upon an enlarged wheel 3, as above described, said wheel also serves the purpose of a counter-balancing wheel, whereby the machine is steadied during the operation thereof, and is enabled to run more smoothly than would be the case otherwise.

Upon a stud 10, mounted in the main frame, is a rocking yoke 11, in the upper ends of the arms of which are supported at one end the rods 12, 13. At their other ends these rods are connected by a cross bar 14, which is supported for vertical adjustment in any convenient manner, as, for instance, by means of a leg 15. In the preferred form shown, the leg 15 is secured to the cross-bar 14 by means of a bolt 16, arranged to extend through the cross-bar and through a longitudinal slot 17, in the leg. By this construction it will be seen that the cross-bar 14, and hence the ends of the rods 12, 13, connected thereby, may be raised and lowered as desired, the yoke support for the other ends of said rods rocking upon the stud 10 during such vertical adjustment. The rods 12, 13 are arranged to extend in parallel relation with respect to each other and with respect to the plane of action of the rotary cutter 2, and afford guiding supports for a reciprocating table 19, said table carrying guide boxes 20 upon the under side thereof, through which the rods 12, 13 pass. Relative reciprocating movements may be imparted to the table and rotary cutter in any convenient manner. In the particular form shown, to which, however, my invention is not to be limited or restricted, and as above indicated, the table 19 is reciprocated, being supported and guided by the rods 12, 13, and in a line parallel with the plane of action of the rotary cutter. Reciprocations may be imparted to the table 19 in many different ways. I have shown a simple arrangement, as the preferred form, wherein I mount a crank arm 21, on the end of a shaft 22, suitably journaled in the framework, and I interpose a connecting rod or link 23 between the table 19 and said crank arm. As shown, one end of said rod or link is pivotally connected to a block 24, secured to table 19, and at the other end thereof is connected to the

crank arm 21. If desired, means may be provided for varying or adjusting the stroke or extent of reciprocatory movement of the table 19. This may be accomplished in 5 many ways, as, for instance, by adjustably connecting the end of the rod or link 23 to the crank arm 21. To this end, the crank arm 21 may be provided with a series of holes 25, in or through any one of which, according 10 to the desired adjustment, the bolt 26, which secures the rod or link 23 to the crank arm 21, may be received. If desired, and in order to secure steadiness and easy working of the apparatus, the crank arm 21 may be counterweighted, as indicated at 27. Rotations 15 may be imparted to shaft 22 in any convenient way. In the preferred form shown, the shaft 22 is driven from the same source from which the cutter is driven. As one 20 form of driving gearing I have shown a sprocket chain 28, arranged to operate over sprockets respectively mounted on shaft 22 and stud 8. To this end, and in order to secure a variation of speed when desired, I 25 mount two or more sprocket wheels 29, 30, of different sizes on shaft 22, and coöperating sprockets 31, 32, on the sleeve 7, which is mounted on stud 8, the chain 28 being designed to operate over either coöperating 30 pair of sprocket gears according to the speed required. If desired, and in order to maintain tautness in the sprocket chain, a spring-pressed belt tightener 33, may be employed. This belt-tightener is pivotally mounted 35 upon a convenient part of the framework so as to be rocked out of the way when it is desired to shift the sprocket chain 28 from one to the other set of sprockets. A spring 34 serves to yieldingly maintain the belt-tightener pressed against the sprocket chain 40 when in operation, and the belt-tightener should be so constructed as to serve its purposes whether the sprocket chain is on one or the other set of sprocket gears.

45 In suitable bearing boxes 35, 36, carried by table 19, is mounted a rod 37.

38 designates a table, platform or other support, mounted upon to move with table 19 during the reciprocatory movements of the latter, but capable of movement along said 50 table 19 transverse to the line of its reciprocatory movement. This table, platform or support 38, is provided with boxes or bearings 39, 40, arranged to slide upon and to be guided by rod 37, as clearly shown in Fig. 1. The table or support 38 is provided with a rack 41, arranged to be engaged by a worm 42, said worm being mounted upon a stud 43, said stud being supported in bearings 44, 45, 55 carried by table 19. Mounted upon stud 43 to rotate therewith is a ratchet wheel 46, (see Fig. 3). Loosely sleeved upon stud 43, and in inclosing relation with respect to ratchet wheel 46, is a casing 47, from which extends 60 an arm 48. The casing 47 is also provided

with a barrel 49, in which is carried a pawl 50, arranged to coöperate with the teeth of ratchet wheel 46. If desired, and in order to maintain efficient engagement of the pawl 50 with the teeth of ratchet 46, a spring 51 may be arranged within barrel 49, to exert its tension upon pawl 50. The arrangement is such that when casing 47 is rotarily displaced in one direction the pawl 50 will ride loosely over the teeth of ratchet 46, but when said 70 casing is rotarily displaced in the opposite direction the pawl 50 engages the ratchet teeth of ratchet wheel 46 and imparts thereto a corresponding rotary movement. If desired, and preferably, means may be provided for 75 yieldingly maintaining the casing 47 in an initial position and serving to return or restore said casing to such position after it has been rotarily displaced. A convenient arrangement for accomplishing this object is 80 shown, wherein a spring 52, is connected at one end to casing 47, and at the other end to an arm 53, in the form of an extension from the bearing 45 of stud 43.

From the foregoing description it will be 85 seen that by periodically engaging and rock- 90 ing arm 48 of casing 47 from its initial or re- 95 tracted position step by step, rotary move- 100 ment will be imparted to ratchet wheel 46, and hence also to the worm 42, and since the worm 42 is in engagement with the rack 41 of table 38, it will be seen that said table is pro- 105 gressed or advanced in a line transverse to the line of reciprocatory movements im- 110 parted to table 19, while at the same time the table 38 partakes of the reciprocatory move- 115 ments of table 19. The periodic engagement 120 of arm 48 to effect this operation may be accomplished in many specifically different ways. I have shown a simple arrangement, 125 wherein I mount an adjustable slide bar 54 in convenient position upon the frame of the machine to engage the arm 48 at the limit of each stroke or reciprocatory movement of table 19. By suitably adjusting the bar 54 130 toward and from the limit of movement of table 19, the degree and extent of rotary movement imparted to the worm 42 may be regulated. To this end I arrange the adjustable bar 54 with an off-set extension 55, 135 (see Fig. 1) arranged in the path of the end of arm 48. The bar 54 is provided with a longitudinal slot or opening 56 therethrough to afford means for setting said bar into any de- 140 sired position of adjustment, said bar being held in its adjusted position by a bolt and nut 57.

The material to be sliced or cut may be clamped or held in any convenient manner. I have shown a simple arrangement, and the 145 preferred form, wherein at the front end of table 38 I provide the upright rack bars 58, 59, upon which is adjustably mounted and guided for vertical movement a cross-bar 60. This cross-bar coöperates with the corre- 150

sponding cross-bar 61, supported or nesting upon table 38. If desired, and in order to afford an efficient clamping means, the cross-bars 60, 61, may be provided with teeth or spikes 62. The adjustable clamp-bar 60 carries spring-pressed pawls 63, 64, at the respective ends thereof, respectively arranged to coöperate with the teeth of rack-bars 58, 59, the arrangement being such that the cross-bar 60 may be readily lowered by exerting pressure thereon, the pawls 63, 64, in such event riding over the teeth of rack-bars 58, 59, but said bar is prevented from being raised by reason of the engagement of the pawls with the teeth of the rack-bars without first rocking said pawls out of engaging relation with respect to the teeth of the rack-bars. In this manner, the material to be sliced may be efficiently clamped and held by being placed in position upon the lower clamp-bar 61, the upper bar 60 being sufficiently raised, and then simply pressing down upon the upper bar until it clamps with sufficient tightness against the article, in which position the clamp-bar 60 will be held by the pawls 63, 64.

The operation of the machine will be readily understood from the foregoing description, taken in connection with the accompanying drawings, and may be briefly stated as follows. The article to be sliced or cut is placed in position upon the supporting platforms or tables, being, if desired, clamped thereon by the clamping bars 60, 61, of the upper table or plate 38, and projecting forwardly or toward the plane of action of the cutter over or upon the lower table or plate 19. The crank handle 9 is actuated, thereby imparting rotation to the cutter 2. At the same time rotation is imparted to shaft 22, through which the crank arm 21 is rotated, thereby imparting reciprocations to the work-supporting tables 19 and 38, along the guiding supporting rods 12, 13, and in a direction parallel with the plane of action of the cutter, so as to carry the material to be sliced back and forth past the cutter. The speed of the reciprocatory movements thus imparted to the material may be varied with reference to the speed of action of the cutter, as above explained, by shifting the sprocket chain 28 from one to another of the sets of sprocket gears. This is important, in that it enables the relative speed of movement of the material with reference to the cutter to be varied according to the character of the material to be sliced. At each reciprocation of the work-holder the end of adjustable bar 54 is engaged by the arm 48 of the ratchet mechanism through which worm 42 is relatively moved through a given distance, depending upon the position of adjustment of bar 54, thereby imparting a step-by-step feed or advancement of the carrier table 38 along its guiding rod 37, and transverse to

the line of reciprocatory movement imparted thereto, thereby successively advancing the work at each reciprocation and to an equal extent for the next cut to be made. By mounting rods 12, 13, so as to be rocked or swung downwardly, the depth of cut made by the cutter may be regulated and controlled. This is important where the material to be sliced is, say, for instance, bacon, for the reason that the piece of bacon may be sliced only to the skin or rind, instead of completely severing each slice, until the desired number of slices have been cut, when the final cut may be effected entirely through the skin or rind by simply raising the table supporting rods 12, 13, thereby detaching the sliced portion, but with the slices all adhering to the skin or rind of the detached portion, and hence enabling the butcher to remove the skin or rind from all the slices at the same time instead of from the separate individual slices. By this arrangement the article is sliced evenly and smoothly, and in convenient form for handling the sliced product.

From the foregoing description it will be observed that I provide an exceedingly simple and efficient slicing mechanism, employing a rotary knife and a laterally advancing reciprocatory table or work-holder with vertically adjustable tracks upon which the table reciprocates, and wherein the reciprocatory movements of the work-holder are adjustable with reference to the action of the cutter. It will also be seen that the work-holding table 38, with its strap or box guides 39, 40, operating in guide-rod 37, is permitted to be rocked upon such straps or guides so as to raise the rack-bar 41 thereof out of engagement with the worm 42, thereby enabling said table to be advanced or retracted by hand to any desired extent and then replaced in position with the worm 42 in engagement with the rack 41. It will also be seen that I employ a comparatively large supporting wheel 3 for the cutter 2. This enables the cutter supporting wheel to serve also the purpose of a fly-wheel, thereby enabling the apparatus to be run steadily and smoothly, and by providing the crank arm 21 with a counterbalancing projection 27, the apparatus is caused to run more regularly and smoothly during the operation thereof.

While I have described my invention with reference to its use as a meat slicing device, I do not desire to be limited in this respect, as it is obvious that a machine embodying the principles of my invention is equally well adapted for slicing or cutting other substances or materials. It is also obvious that many variations and changes in the details of construction and arrangement of parts would readily occur to persons skilled in the art and still fall within the spirit and scope

of my invention. I do not desire, therefore, to be limited or restricted to the exact details shown and described. But,

Having now set forth the object and nature of my invention and a construction embodying the principles thereof, what I claim as new and useful and of my own invention, and desire to secure by Letters Patent, is:

1. In a meat slicing machine, a rotary cutter, guides pivotally supported at one end and arranged to extend in lines parallel with respect to the plane of action of the cutter, an adjustable support for the free ends of said guides, a work holder mounted to slide upon said guides, means for reciprocating said work holder along said guides, a ratchet mechanism for intermittently advancing said work holder toward the plane of action of the cutter, and means actuated by the reciprocatory movements of said work holder for actuating said ratchet mechanism, as and for the purpose set forth.

2. In a meat slicing machine, a rotary cutter, a pivotally mounted yoke, guide rods supported at one end in said yoke and arranged to extend in lines parallel with respect to the plane of action of the cutter, a vertically adjustable support for the opposite ends of said guide rods, a work-holder mounted to slide upon said rods, and means for reciprocating said work holder along said guides, as and for the purpose set forth.

3. In a meat slicing machine, a rotary cutter, a pivotally mounted yoke, guide rods supported at one end in said yoke and arranged to extend in lines parallel with respect to the plane of action of the cutter, a vertically adjustable support for the free ends of said rods, a work-holder mounted to reciprocate along said guide rods, and means actuated by the reciprocatory movements of said work holder for intermittently advancing the same automatically toward the plane of action of the cutter, as and for the purpose set forth.

4. In a meat slicing machine, a rotary cutter, and a reciprocatory table, a guide rod carried by said table and extending transverse to the line of reciprocatory movement thereof, a supplemental table having guiding engagement with said rod at one end and a rack at the opposite end thereof, a worm arranged to engage said rack, and means for intermittently rotating said worm, as and for the purpose set forth.

5. In a meat slicing machine, a rotary cutter, and a reciprocatory table, a guide rod extending in a line transverse to the line of reciprocatory movement of said table, a supplemental table having guiding straps at one edge thereof operating upon said rod and forming a hinge connection, said supplemental table provided with a rack at the opposite edge thereof, a ratchet mechanism with

which said rack detachably engages, and means for intermittently operating said ratchet mechanism, as and for the purpose set forth.

6. In a meat slicing machine, a slicing cutter and a table mounted for relative reciprocatory movement, a supplemental table mounted to move transverse to the line of relative reciprocatory movement and carrying a rack at one side edge thereof, a worm arranged to engage said rack, a ratchet gear connected to rotate with said worm, a loosely sleeved casing carrying a pawl engaging said ratchet gear, an arm connected to said casing, and a stationary adjustable engaging bar arranged to engage said arm to actuate said casing, as and for the purpose set forth.

7. In a meat slicing machine, a rotary cutter, a reciprocatory table, a supplemental table mounted for movement upon said first-mentioned table in a line transverse to the line of reciprocatory movement thereof, a rack connected to said supplemental table along one side edge thereof, a stud carried by said first-mentioned table to reciprocate therewith, a worm and a ratchet gear mounted upon said stud to rotate therewith, a casing sleeved over said ratchet gear and carrying a pawl engaging said gear, an arm connected to said casing, a stationarily mounted adjustable bar arranged in the path of said arm to rotatively displace said casing, and means for returning said casing to initial position, as and for the purpose set forth.

8. In a meat slicing machine, a main frame, a cutter shaft and a countershaft journaled therein, a drive mechanism arranged to rotate both of said shafts, a cutter carried by said cutter shaft, guide rods pivotally mounted at one end and supported for vertical adjustment at the other end, a work holder mounted to slide on said rods, and means actuated by said countershaft for reciprocating said holder on said rods past the cutter, as and for the purpose set forth.

9. In a meat slicing machine, a main frame made in one piece, a cutter shaft and a countershaft journaled therein, guide rods pivotally connected to said main frame at one end, means for adjusting the height of the other ends of said rods, a work holder mounted to slide on said rods, a cutter mounted on said cutter shaft, and connections between said countershaft and work holder for reciprocating the latter, as and for the purpose set forth.

In witness whereof, I have hereunto set my hand this first day of March 1904, in the presence of the subscribing witnesses.

FRANKLIN P. BURKHARDT.
